UNITED STATES PATENT OFFICE.

KARL FUHR, OF BIELEFELD, GERMANY.

METHOD OF MANUFACTURING RESONANCE BODIES ESPECIALLY FOR MUSICAL INSTRUMENTS.

Application filed July 6, 1927, Serial No. 203,846, and in Germany May 21, 1926.

For making resonance bodies, as f. i. top and bottom sound boards for violins, the obtaining of good sounding qualities for all sorts of tones was regarded as a matter of 5 personal experience and skill. It was understood, that the tone peculiar to a resonance body is therefore of importance, and different methods for investigating that tone were used. For example, the plate, which has to 10 be investigated, is fixed in a clamp or between a cork and a finger and touched by a bow at its edge. Or the plate is hung free by a string and knocked by the knuckle. All these methods have the disadvantage, that the plate 15 is treated in the whole and the peculiar tone of the whole plate only can be investigated.

The invention relates to a method and a device for manufacturing resonance bodies with vibration qualities, which can be fixed 20 with exactness in advance. This is obtained by stating the peculiar vibrations and the peculiar tone of the parts in the whole and in different places at different steps of the manufacturing process. For this purpose by 25 means of a small wand which is brought into longitudinal vibrations, the peculiar tone and vibration are heard and the respective parts of the body accordingly worked out. By the new method resonance bodies of a high grade 30 of perfectness can be produced on a technical base of great exactness for violins, cellos, mandolines, guitars, sounding diaphragms, loud speakers and the like, because not only the peculiar tone of a single part of the instrument, as f. i. the bottom sound board, but 35 also the peculiar vibration of any place of any part during each step of the manufacturing process can be stated and the said process accordingly arranged.

40 The device for the new method consists of a small glass wand, which is placed vertically on the part, which has to be worked and therefore investigated in respect to its peculiar own tone, and brought into longitudinal vibrations by striking it lengthwise by a finger wetted with water. In the respective place of the resonance body cross vibrations 45 are hereby produced noticeable by a note of a certain highness. This tone is the result of 50 the vibrations of the resonance body produced by passing two wetted fingers lengthwise

along its surface and the body of the small glass wand. In order to reduce the influence of the last, the glass wand is made preferably hollow.

55 The size of the glass wand is chosen according to the size of the resonance body. F. e. for parts of a violin or the violin itself a glass wand of about 1,3 mm. in thickness and 70 mm. in length would be adequate; for a 60 cello a glass wand of 2,25 mm. in thickness and 100-150 mm. in length would be used.

A further advantageous feature of the invention consists in providing the end of the glass wand with a small ball or cap of glass, 65 sealing wax or the like or by melting the glass wand end to an adequate form. The body, which has to be treated, is hereby protected from scratching or damaging by the sharp edges of the wand and an easy and quick handling is possible.

70 The drawing represents the invention by way of an example,

Fig. 1 showing the use of the device on a plate;

75 Fig. 2 showing in an enlarged scale the lower end of the small glass wand.

The glass wand 1 is taken at its upper end by two wetted with water fingers 2 and 3 of one hand, put on the resonance plate 4 in 80 the place, which has to be investigated for working, and brought by striking downwards by the fingers into longitudinal vibrations, which produce cross vibrations of the plate. The tone produced hereby indicates, if the 85 plate is worked correctly or needs any correction.

Fig. 2 shows a small glass wand 1 with a cap 5 fixed to its lower end in order to protect the body, f. e. a ready finished and varnished violin, from scratching.

90 I claim:

1. A method for manufacturing resonance bodies especially for musical instruments, consisting in bringing an auxiliary body into 95 contact with any place of the resonance body and into longitudinal vibrations by rubbing so as to bring said place into cross vibrations peculiar to said place, so that the kind of said cross vibrations is stated, and accordingly 100 working said place until the desired kind of vibrations is produced.

2. A device for manufacturing resonance bodies, consisting in a wand of hard and elastic material, such as glass, the size of said wand with respect to the body to be manufactured being the smallest sufficient for setting said body into vibrations.

3. A device for manufacturing resonance bodies, consisting in a hollow wand of hard and elastic material, such as glass, the size 10 of said hollow wand with respect to the body

to be manufactured being the smallest sufficient for setting said body into vibrations.

4. A device for manufacturing resonance bodies, consisting in a small wand of hard and elastic material, such as glass and a protecting cap of similar and smooth material on one end of said wand. 15

In witness whereof I affix my signature.

KARL FUHR.
